(57) **CLAIM**

The ornamental design for an electronic still camera, as shown and described.

DESCRIPTION

FIG. 1 is a front, top side perspective view of an electronic still camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the right of FIG. 2;

FIG. 7 is a side elevational view thereof from the left of FIG. 2;

FIG. 8 is a front, top side perspective view thereof, with the lens retracted; and,

FIG. 9 is a right side elevational view thereof, with a lens retracted and a flash unit in an open position.
